UNITED STATES PATENT OFFICE

152,971

DESIGN FOR A CHILD'S DOLL

Bertha E. Honeck, Milwaukee, Wis.

Application November 29, 1947, Serial No. 142,882

Term of patent 7 years

(Cl. D34—4)

To all whom it may concern:

Be it known that I, Bertha E. Honeck, a citizen of the United States, residing at Milwaukee, in the county of Milwaukee and State of Wisconsin, have invented a new, original, and ornamental Design for a Child's Doll, of which the following is a specification, reference being had to the accompanying drawing, forming a part thereof, and in which:

I claim:

The ornamental design for a child's doll, as shown.

BERTHA E. HONECK.
